(57) **CLAIM**

We claim the ornamental design for stilt, as shown and described.

DESCRIPTION

FIG. 1 is a perspective view of the third embodiment of our ornamental design of the stilt;

FIG. 2 is a close-up view of FIG. 1;

FIG. 3 is a left side elevation view of the stilt of FIG. 1;

FIG. 4 is a front elevation view of the stilt of FIG. 1;

FIG. 5 is a right side elevation view of the stilt of FIG. 1;

FIG. 6 is a rear elevation view of the stilt of FIG. 1;

FIG. 7 is a top plan view of the stilt of FIG. 1; and,

FIG. 8 is a bottom plan view of the stilt of FIG. 1.

The broken lines shown are included for the purpose of illustrating portions of the article which form no part of the claimed design.
